ENGINE

Harold H. Timian, Detroit, Mich., assignor to
 Continental Motors Corporation, Detroit, Mich.,
 a corporation of Virginia

Application December 12, 1931, Serial No. 580,528

22 Claims. (Cl. 123—52)

This invention relates to internal combustion engines and more particularly to a fuel mixture distributing device for conducting and distributing the fuel mixture to the respective cylinders.

5 My invention is of special importance when utilized with a multi-cylinder engine and in conjunction with a fuel mixture distributing device constructed with a multiplicity of outlets adapted for separate operative connection with the respective engine cylinders. My engine is especially suitable for use with an engine of the sleeve valve type wherein it has been found desirable to introduce the fuel mixture to the engine cylinders in the manner as shown in the illustrated embodiment of my invention. It is understood, however, that my invention in its broadest aspects need not be limited to engines of the sleeve valve type since the principles of my invention may be embodied in engines other than the sleeve valve type, and in engines other than that type in which the fuel mixture is separately conducted to each of the cylinders.

An object of my invention is to effect a predetermined fuel mixture distribution for multi-cylinder internal combustion engines by providing an intake manifold structure adapted for providing a fuel mixture distribution tending to effect an improved performance in the operation of the engine.

30 Another object of my invention is to provide the improved fuel mixture distributing device for multi-cylinder in-line engines by providing the manifold structure with a plurality of outlets and associated means for effecting a predetermined distribution of the fuel mixture to said outlets.

Another object of my invention is to provide an improved fuel mixture distributing device for a multi-cylinder internal combustion engine in which the intake cycle of one of the engine cylinders overlaps with respect to the intake cycle of another engine cylinder by providing means for equalizing the fuel mixture flow to counteract the tendency towards unequal distribution as induced by the overlapping intake cycles of some of the engine cylinders.

For a more detailed understanding of my invention, reference may be had to the accompanying drawings which illustrate one form which my invention may assume, and in which:

50 Fig. 1 is a vertical sectional view through an engine of the sleeve valve type illustrating my improved fuel mixture distributing device associated therewith.

55 Fig. 2 is a fragmentary plan sectional view of my improved fuel mixture distributing device,

Fig. 3 is a fragmentary vertical sectional view thereof taken substantially on the line 3—3 of Fig. 2.

Figs. 4, 5 and 6 are transverse sectional views taken respectively on the lines 4—4, 5—5 and 6—6 of Fig. 3.

Fig. 7 is a diagrammatic view of an intake manifold structure for a six cylinder engine constructed in accordance with my invention.

Fig. 8 is a diagrammatic view illustrating the 10 manifold structure as shown in Fig. 7 in plan, as viewed from the line 8—8 of Fig. 7.

Fig. 9 is a diagrammatic elevational view of an intake manifold structure associated with an up-draft carburetor,

Fig. 10 is a diagrammatic plan view illustrating 15 a modified form of construction,

Fig. 11 is a detailed sectional view taken substantially on the line 11—11 of Fig. 10,

Fig. 12 is a diagrammatic plan view illustrating 20 a further modified form of construction,

Figs. 13 and 14 are detail vertical sectional views illustrating two types of deflecting means which may be incorporated in a fuel mixture distributing device of the type herein illustrated.

In view of the fact that very beneficial results are obtained with the use of a fuel mixture distributing device of the character hereinafter described with a sleeve valve engine, I have chosen for purposes of illustration to show my invention 30 as incorporated with the sleeve valve engine having a plurality of cylinders preferably arranged in line. It will be noted that my invention in its broadest aspects need not be limited to use with a sleeve valve engine since the novel features of my invention may be incorporated in engines other than the sleeve valve type. In the accompanying drawings I have illustrated an engine of the single sleeve valve type which in general includes a crankcase 10 having a plurality of 35 cylinders 11 in which a sleeve valve 12 is operably supported. A piston 13 preferably reciprocates within the sleeve valve means and is connected with the crankshaft 14 by means of a connecting rod 15. A cylinder head 16 is preferably secured to the engine block and is provided with a portion 17 depending within the cylinder and spaced from the walls thereof to provide a sleeve pocket for accommodating the upper portion of the sleeve valve means.

The said sleeve valve 12 is provided with intake and exhaust ports 18 and 19 respectively cooperating with the cylinder intake and exhaust ports 20 and 21. In the illustrated embodiment of my invention I have chosen for purposes of illus- 50 55

tration to provide a single sleeve valve 12 of the Burt-McCollum type which is given a combined reciprocating and oscillating movement with respect to the cylinder and sleeve axes in a well 5 know manner wherein any point on the sleeve traverses a closed path. Movement to the sleeve valve means is imparted thereto by means of a wobble shaft 22 having wobble cranks 23, said cranks being connected with the sleeve 12 by 10 means of the link 24 and the ball and socket structure 25.

An intake manifold structure A is associated with the engine and constructed to distribute the fuel mixture to the respective engine cylinders. 15 A suitable exhaust manifold B may also be associated therewith for collecting the exhaust gases and conducting same to a distant point.

In the preferred construction as shown in the accompanying drawings, I have provided the engine with a carburetor C having a downwardly extending fuel conducting portion 26 adapted to be connected with the fuel conducting conduit 27 of the manifold structure which extends generally upwardly from the remaining parts of the 20 fuel mixture distributing device. The manifold structure provides the lateral runner portions A¹ and A² which are preferably extended in opposite directions and are each provided with a plurality of port outlets. These outlets in the lateral runner portions A¹ and A² are respectively numbered 25 from 1 to 8 inclusive and are adapted for separate connection with the cylinders of the engine which may be respectively numbered 1', 2', 3', 4', 5', 6', 7', 8' by means of the port runner portions 30 a¹, a², a³, a⁴, a⁵, a⁶, a⁷, a⁸. These port outlets are 35 preferably spaced longitudinally of the lateral runner portions and it may be noted that the port outlets 1 to 4 inclusive are associated with the lateral runner A¹ while the port outlets 5 to 8 inclusive are associated with the lateral runner portion A². It may also be noted that the lateral runners A¹ and A² extend in opposite directions 40 and in general provide a continuous fuel mixture distributing portion to which the plurality of port runner portions communicate.

A manifold structure comprising a header and a plurality of branch portions is not broadly novel but the means associated therewith as illustrated by my present invention provides means for controlling the fuel mixture distribution in such a way as to make this type of structure practical for 50 commercial use. The distribution of wet fuel in a manifold of this type is difficult to obtain because of the ramming effect resulting from this construction and also because of the unequal distribution of the wet parasitic fuel on acceleration unless some means are provided for counteracting the tendency of the wet fuel particles lying in the form of a film on the floor of the manifold to 55 sweep into the end cylinders 1' and 8'. In my present invention I have counteracted this tendency towards unequal distribution on acceleration of the engine without upsetting the general distributing characteristics of the fuel mixture distributing device by providing baffles or other suitable protuberances 30 within the fuel mixture distributing portion of the manifold structure. In this case I have preferably arranged these baffles adjacent the port outlets 2, 3, 6 and 7 and 60 I have preferably provided said baffles with a deflecting wall 29 inclined to the axis of the lateral runners and inclined with respect to the port outlets associated therewith in such a manner as to deflect the precipitated wet fuel and to effect a 65 predetermined distribution to said port outlets of 70 75

said wet fuel in the manifold and normal fuel mixture as received from the fuel mixture forming means or carburetor. It will be noted that in the construction illustrated that these baffles or protuberances are located substantially central with respect to the longitudinal axis of the lateral runner and are spaced from both side walls thereof. This construction provides a substantial uniform distribution but obviously my invention in its broadest aspects is not limited to 10 a precise construction as herein illustrated since different conditions and different engine designs may necessitate the construction of more or less baffles of various sizes, shapes, etc. and said baffles may be located at other points than illustrated 15 and arranged in various positions with respect to the axis of the lateral runners. The exact construction and position of these baffles may be best determined by experiment and in the experiments performed by applicant in arriving at a construction suitable for an engine of the type herein illustrated, the construction shown in Fig. 2 was found to be quite satisfactory.

Figures 13 and 14 illustrate baffles of different construction and as herein illustrated these baffles 25 30' and 30'' shown respectively in Figs. 13 and 14, extend from the floor 31 of the lateral runner to the roof 32. The cross-sectional construction of these baffles 30' and 30'' may be varied in such a manner as to obtain a predetermined distribution 30 of the fuel mixture at various engine speeds. The advantage of this type of construction may be apparent when it is remembered that the fuel mixture flows through the lateral runner in a strata formation, the densest portion of the fuel mixture flow lying at different elevations within the runner at different engine speeds. Thus to obtain the correct distribution, it may be necessary to vary the cross-sectional construction of the baffle in order to obtain the correct action on the 40 fuel mixture flow, the baffles being constructed to act upon the fuel mixture flow of relatively greatest density so as to provide proper distribution at various engine speeds.

A further control of the fuel mixture distribution and in particular the distribution of the wet fuel particles may be obtained by positioning some of the ports in such a manner as to provide an obstruction or dam adjacent the mouth of the port runners. This is illustrated in Figs. 2 and 3 50 and shows the port outlets 4 and 5 spaced upwardly from the floor 31 of the lateral runners. These port outlets 4 and 5 being closely adjacent to the fuel mixture conducting means 27 leading from the carburetor, tend to receive a larger 55 quantity of the wet fuel particles on acceleration and during the operation of the engine due to the fact of their position and in order to counteract this tendency the said ports are constructed in a manner as herein illustrated.

In Figs. 10 to 12 inclusive I have illustrated a modified construction for obtaining proper fuel mixture distribution and in particular the distribution of the wet fuel particles by providing depressions 40 adjacent some of the port outlets. 60 As shown in Fig. 10, these depressions 40 are located in such a manner as to extend inwardly of the port runner 42 in the floor thereof. Thus as the wet fuel particles flowing along the floor reach the depression a portion of the fuel is 65 trapped within the depression where it may be swept into the associated port runner with a minimum of resistance. Preferably these depressions extend approximately half way across the floor of the runner and it is obvious that the dis- 70 75 75

tribution to the associated port runners may be varied by varying the dimensions of the depression. In Fig. 12 I have provided a depression 40' associated with one of the port outlets 42' 5 and a baffle 41 associated with another of the port outlets. In some instances the construction as illustrated in Fig. 12 will be preferable for obtaining the required fuel mixture distribution.

In Figs. 2 and 3, I have illustrated my construction as being incorporated with a manifold structure adapted for use with an eight cylinder in line engine, but it is obvious that the principles of my invention as described above may be incorporated in engines of the 4 or 6 cylinder type. 15 In Figs. 7 to 9 inclusive, I have illustrated diagrammatically manifold structures adapted for association with a 6 cylinder in line engine. In Fig. 7, I have illustrated a manifold structure adapted for association with a downdraft carburetor and have provided a baffle 50 substantially similar to the baffle 30 employed with the manifold illustrated in Fig. 2. In Fig. 8, I have illustrated another baffle 50' of a different width and different position with respect to the longitudinal axis of the lateral runner than the baffle 50, it being advisable in some instances to provide the baffles of different widths and different locations in order to obtain the required distribution. 25 In Fig. 9, I have illustrated a manifold structure which in general is of the type illustrated in Fig. 7 but is provided with a fuel mixture conducting portion of different construction. The fuel mixture conducting portion 27' shown in Fig. 9 is of the type adapted for use with an up draft carburetor.

In some engines, and in particular those of the type employing 8 or more cylinders in line, it is quite desirable in some instances to employ a crankshaft so constructed and cooperatively associated with valving means that the intake cyclical event of some of the engine cylinders will overlap with respect to the intake cyclical event of other engine cylinders. For purposes of illustrating this principle I have chosen to illustrate an engine of the 8 cylinder in line type in which the intake cyclical event of cylinder 4' overlaps with that of cylinder 1' and the intake cyclical event of 5' overlaps with that of cylinder 8'. As a result of this condition it is apparent that 45 during a portion of the engine operation the engine cylinders 1', 4' and 5', 8' are drawing fuel mixture from the intake manifold simultaneously. Thus unless means are provided for supplying additional fuel mixture during this overlapping period of the cylinders these cylinders above referred to will be starved. The velocity at which the fuel mixture flows through the lateral runner associated with these overlapping cylinders remains substantially constant and in order to provide means for supplying an adequate supply of fuel mixture to these cylinders I have provided an enlargement 60 of the lateral runner in such a way as to permit a greater volume of fuel mixture to be conducted to the lateral runner. This 55 difficulty may be readily overcome in an 8 cylinder in line engine because of the fact that the middle cylinders 4' and 5' which overlap with respect to the end cylinders, lie adjacent to the primary fuel mixture conducting means 27. In engines of more than 8 cylinders the overlapping cylinders 60 may not lie adjacent the primary fuel conducting portion of the manifold structure and thus may present some difficulties but the principle as shown in my invention may be thus utilized to 70 overcome the difficulty if so desired. However,

my invention has special reference to an 8 cylinder engine and by enlarging the lateral runner adjacent the middle port outlets 4 and 5 as at 60 which lie adjacent to the primary fuel mixture conducting portion 27, it will be seen that the end port outlets 1 and 8 associated with the end cylinders 1' and 8' will not be starved since the additional amount of fuel mixture needed for supplying these overlapping cylinders 1', 4' and 5', 8' is taken care of by the enlarged runner portion 60 as described above. 10

It will be further noted that the inner vertical edges 4^a and 5^a of the middle port outlets are substantially flush with the inside wall of the primary fuel conducting means 27 and the said lateral runners and associated port outlets are 15 preferably symmetrically arranged with respect to the axis of the primary fuel mixture conducting means.

The length of the port runners a¹ to a⁸ inclusive is of special importance in connection with the sleeve valve engine of the type illustrated in the accompanying drawings. In sleeve valve engines it is quite essential that the fuel mixture be conducted substantially symmetrical 25 into the intake chambers 70 in order to not upset any of the swirl control devices usually incorporated with engines of this character. In order to straighten out the fuel mixture flow it is found that these port runners should have a 30 length substantially 2.4 times the manifold width in order to direct the fuel mixture flow straight into the intake chamber 70 with a minimum of resistance. With the construction as herein illustrated I have thus provided an intake manifold structure particularly adapted for use with a sleeve valve engine and have provided a fuel mixture distributing device constructed and arranged to conduct the fuel mixture to each engine cylinder by means of individual port runners thus making it possible to more efficiently 40 control the swirl in the engine cylinder by means of the usual swirl controlling devices. 35

It will be noted that I have provided a fuel mixture distributing device of novel construction and of an arrangement which can be readily incorporated in production manufacturing. The devices by which I obtained the predetermined distribution of the fuel mixture do not require elaborate production operations, and as a result full advantage may be taken of the improvements herein described and claimed with a minimum of expense and no adjustments or other adjustable controls are necessary in obtaining the desired distribution of the fuel mixture 55 throughout the engine speed range. 45

It will be apparent to those skilled in the art to which my invention pertains that various modifications and changes may be made therein without departing from the spirit of my invention or from the scope of the appended claims. 60

What I claim as my invention is:

1. A fuel mixture distributing device for a multi-cylinder internal combustion engine and including a distributing portion having a plurality of port outlets including end and intermediate outlets and adapted for communication with the engine cylinders, and means within the distributing portion and spaced from the side walls thereof for uniformly distributing the fuel 70 flow to said port outlets. 65

2. A fuel mixture distributing device for a multi-cylinder internal combustion engine and including a distributing portion having a plurality of port outlets including end and inter- 75

mediate outlets and adapted for communication with the engine cylinders, and means within the distributing portion and spaced from the side walls thereof, said means having an angular relation with respect to said port outlets whereby to deflect the fuel towards said respective intermediate port outlets for uniformly distributing the fuel flow thereto.

3. A fuel mixture distributing device for a multi-cylinder internal combustion engine and including a distributing portion having a plurality of port outlets including end and intermediate outlets and adapted for communication with the engine cylinders, and means including a deflecting member within the distributing portion and spaced from the side walls thereof, said member acting on the fuel to deflect same towards the intermediate port outlets for uniformly distributing the fuel flow to said port outlets.

10 4. A fuel mixture distributing device for a multi-cylinder internal combustion engine and including a distributing portion having a plurality of port outlets including end and intermediate outlets and adapted for communication with the engine cylinders, and means within the distributing portion and including a baffle spaced from said port outlets and from the side walls of said distributing portion, said baffle having a deflecting wall angularly inclined with respect to 15 said fuel flow to deflect portions of same towards the intermediate port outlets whereby to provide a predetermined distribution of the fuel mixture to said port outlets.

10 5. A fuel mixture distributing device for a multi-cylinder internal combustion engine and including a distributing portion having a plurality of port outlets including end and intermediate outlets and communicating with the engine cylinders, and means including a device spaced from 20 the side walls of the distributing portion and constructed to act upon the fuel flow to successively deflect predetermined amounts thereof from said intermediate fuel stream whereby to effect a substantially uniform distribution of the fuel to said port outlets.

15 6. A fuel mixture distributing device for a multi-cylinder internal combustion engine and including a distributing portion comprising lateral runners each having a plurality of port outlets including end and intermediate outlets and communicating with the engine cylinders, the floor of said lateral runner having a depression adjacent one or more of said intermediate port outlets for effecting the withdrawal of predetermined amounts of fuel from the fuel stream 25 whereby to effect a substantially uniform distribution of the fuel mixture to said port outlets.

10 7. A fuel mixture distributing device for a multi-cylinder internal combustion engine and including a distributing portion having a plurality of port outlets adapted for communication with the engine cylinders, the floor of said distributing portion having a depression adjacent one or more of said port outlets for effecting a predetermined distribution of the wet fuel to said 30 port outlets, and a deflecting member within said distributing portion and associated with said port outlets for effecting a further predetermined distribution of said fuel flow to said port outlets.

15 8. A fuel mixture distributing device for a multi-cylinder internal combustion engine having fuel mixture forming means, said device including a manifold structure cooperatively associated with said fuel mixture forming means and having

5 lateral runners each provided with a plurality of port outlets including end and intermediate outlets, and means within said runners and spaced from the side walls thereof for effecting a predetermined fuel flow distribution to said port outlets.

9. A fuel mixture distributing device for a multi-cylinder engine and including a manifold structure having lateral runners each provided with a plurality of port outlets spaced longitudinally thereof, and means including deflecting members located within said lateral runners and spaced from both side walls thereof for effecting a predetermined distribution of the fuel flow to 10 said port outlets.

15 10. A fuel mixture distributing device for a multi-cylinder engine and including a runner portion having a plurality of port outlets adapted for communication with the engine cylinders, said runner portion having intermediate baffles 20 of varying predetermined cross section constructed to act on said fuel flow for effecting a predetermined distribution of said fuel to said port outlets.

25 11. A fuel mixture distributing device for a multi-cylinder engine and including a manifold structure having a lateral runner provided with a plurality of port outlets spaced longitudinally of the runner, one of said port outlets having a lower edge offset with respect to the floor of the 30 runner.

35 12. A fuel mixture distributing device for a multi-cylinder engine and including a manifold structure having a lateral runner provided with a plurality of port outlets, one of said port outlets having a lower edge offset with respect to the floor of the runner, and means within 40 said runner and including one or more fuel flow deflecting devices adjacent to one or more of said port outlets for deflecting a predetermined amount of the fuel flow respectively to said port outlets.

45 13. A fuel mixture distributing means for a multi-cylinder internal combustion engine having cylinder intake ports and associated devices 45 for controlling the introduction of fuel mixture into the cylinders constructed and arranged for providing overlapping intake cyclical events; said means including a fuel mixture conducting portion having a plurality of port outlets communicating with the engine cylinders, said conducting portion including an enlarged portion cooperating with a port outlet associated with a cylinder having an intake cyclical event overlapping the intake cyclical event of another cylinder to maintain substantially constant fuel mixture velocities in said conducting portion for equalizing the charge variations due to the overlapping of said cyclical events.

50 14. A fuel mixture distributing means for a multi-cylinder internal combustion engine having cylinder intake ports and associated devices for controlling the introduction of fuel mixture into the cylinders constructed and arranged for providing overlapping intake cyclical events; said 55 means including oppositely extending lateral runners each provided with a plurality of port outlets spaced longitudinally thereof, said port outlets adapted for communication with the engine cylinders, the lateral runner adjacent the port outlet associated with the cylinder having an intake cyclical event overlapping the intake cyclical event of another cylinder being enlarged to provide a relatively greater cross-sectional area per- 70 75

mitting the equalization of charge variations due to said overlapping of said cyclical events.

15. A fuel mixture distributing device for a multi-cylinder engine and including a manifold structure having a primary fuel mixture con-

ducting means and lateral runner portions having a plurality of port outlets spaced longitudinally thereof and being enlarged adjacent the junction with said primary conducting means, said en-

10 larged portion extending beyond the port outlet next adjacent to the said primary conducting means.

16. A fuel mixture distributing device for a multi-cylinder engine and including a manifold structure having a primary fuel mixture con-

ducting means and lateral runner portions communicating therewith, said lateral runner portions having a plurality of port outlets spaced longitudinally thereof, one of said port outlets

20 in each lateral runner portion being located adjacent the junction of said primary fuel mixture conducting means and the lateral runner portion, the runner portion adjacent to said last men-

25 tioned port outlet being enlarged to accommodate a greater volume of fuel mixture flow without materially varying the velocity of flow.

17. A manifold structure for a multi-cylinder engine including a conducting portion having a port outlet intermediate the ends thereof, and

30 means associated with said intermediate outlet for dropping fuel precipitate below the conducting portion floor level for introduction into said intermediate outlet.

18. A manifold structure for a multi-cylinder engine including a conducting portion extending longitudinally of the engine and a plurality of port runners, said portion adapted for carrying fuel precipitates, and means for dropping a portion of said fuel precipitate at points intermediate

40 the length of said conducting portion for introduction into said port runners, whereby to effect substantially uniform distribution of said fuel precipitates to said engine cylinders.

19. A manifold structure for a multi-cylinder engine including a conducting portion extending longitudinally of the engine and port runners connected therewith, said portion adapted for carrying fuel precipitates, and means for suc-

45 cessively dropping predetermined portions of said

fuel precipitates at spaced points intermediate the length of said conducting portion for introduction into said port runners whereby to effect substantially uniform distribution of said fuel precipitates to said engine cylinders.

20. A manifold structure for a multi-cylinder engine including a conducting portion extending longitudinally of the engine and adapted for car-

rying fuel precipitates, said conducting portion having a port outlet at one end and a plurality of intermediate port outlets, said port outlets each

communicating with an engine cylinder, and means including a baffle within said conducting portion respectively associated and cooperating

with said intermediate port outlets for deflecting predetermined amounts of the fuel precipitates towards said associated intermediate port outlets

10 whereby to effect substantially uniform distribution of said fuel precipitates to said engine cylinders.

21. A manifold structure for a multi-cylinder engine including a conducting portion extending longitudinally of the engine and adapted for car-

rying fuel precipitates, said conducting portion having a port outlet at one end and a plurality of intermediate port outlets, said port outlets each

communicating with an engine cylinder, and baf-

fles extending transversely within said conducting portion adjacent the far side of the port outlets

15 in the direction of fuel travel for deflecting pre-

determined amounts of the fuel precipitates to-

wards said intermediate port outlets whereby to

effect substantially uniform distribution of said

fuel precipitates to said engine cylinders.

22. A fuel mixture distributing device for a multi-cylinder internal combustion engine in-

cluding a fuel mixture conducting portion ex-

tending longitudinally of the engine and having a plurality of outlet ports spaced longitudinally

thereof and communicating with the engine cylin-

ders, and means including wet fuel deflecting de-

vices spaced longitudinally within the conduct-

ing portion and acting on the wet fuel precipitate

flowing therethrough for successively deflecting

predetermined amounts of the fuel towards the

40 intermediate outlet ports whereby to counteract

the tendency of said deflected fuel to flow past

45 said intermediate ports into the end outlet port.

HAROLD H. TIMIAN.
